UNITED STATES PATENT OFFICE.

CHARLES W. COWELL, OF NOVINGER, MISSOURI, ASSIGNOR OF ONE-HALF
TO JAMES C. SEFTON, OF TROY, ILLINOIS.

COAL-DRILL.

No. 801,853.

Specification of Letters Patent.

Patented Oct. 17, 1905.

Application filed July 11, 1904. Serial No. 216,013.

To all whom it may concern:

Be it known that I, CHARLES W. COWELL, a citizen of the United States, residing at Novinger, Adair county, State of Missouri, have 5 invented certain new and useful Improvements in Coal-Drills, of which the following is a specification containing a full, clear, and exact description, reference being had to the accompanying drawings, forming a part hereof.

10 My invention relates to coal-drills; and it consists of the novel features herein shown, described, and claimed.

In the drawings, Figure 1 is a perspective of a coal-drill embodying the principles of my 15 invention. Fig. 2 is an enlarged detail illustrating the construction of the drilling mechanism. Fig. 3 is a view showing the coal in section and illustrating the operation of the drill. Fig. 4 is a cross-section on the line 4 4 20 of Fig. 3. Fig. 5 is an end elevation showing the chucks for holding the bits. Fig. 6 is a side elevation showing the bits in the chucks. Fig. 7 is a front elevation of the longest and narrowest bit. Fig. 8 is a front elevation of 25 the intermediate bit. Fig. 9 is a front elevation of the shortest and widest bit. Fig. 10 is a cross-section of the feed-screw on the line 10 10 of Fig. 2.

Referring to the drawings in detail, the 30 feed-screw 11 has two oppositely-arranged key-seats 12 and 13, as shown in Fig. 10. The feed-screw 11 is mounted and operated in the usual way, as shown in Fig. 1. The drill-shank 14 has a straight opening or bore 15 35 extending from one end to the other, and the head 16 of the drill-shank is enlarged and has a tapered opening 17, connecting with the opening 15 to receive the point of the feed-screw 11, said point being squared, and the 40 opening 17 being correspondingly squared to prevent rotation of the feed-screw relative to the drill-shank, and a spring-cotter 18 is inserted through the head 16 and through the point 19 of the feed-screw to hold the feed-screw and drill-shank removably together. The coal-conveyer threads 20 21 22 extend 45 from the point of the drill-shank 14 to the head 16, said threads being arranged parallel and spiral. The bit-holders 23 24 25 are 50 formed on the back sides of the coal-conveyer threads 20 21 22 and have sockets 26 to receive the shanks of the bits and set-screws 27 to hold the shanks in position. The bits 28 29 30 each have a shank 31 to be inserted into the

55 sockets 26 and are engaged by the set-screws 27. The bit 28 is, say, three-eighths of an inch wide and five-eighths of an inch long. The bit 29 is shorter and wider than the bit 28, and the bit 30 is shorter and wider than the bit 29, so that when the bits are arranged in 60 rotation, as shown in Fig. 6, the bit 28 will cut a narrow groove 32, the bit 29 will follow the bit 28 and widen the groove, as indicated by 33, and the bit 30 will follow the bit 29 and finish the groove, as indicated by 34, 65 the finished part 34 being wide enough to receive the drill-shank 14 and the coal-conveyer threads 20 21 22, as shown in Figs. 3 and 4, thus leaving a core 35 of coal in the bore 15.

In an ordinary coal-drill forming a hole two 70 and one-half to three inches in diameter the bit 30 should be from one-half to five-eighths of an inch in width, so that the finished groove 34 will make a core 35 somewhat smaller than the bore 15 and will make an opening 36 somewhat larger than the diameter of the threads 20 21 22, so that the drill will slide readily backward or forwardly in said opening. The core 35 will break loose from the coal bank at 75 frequent intervals and will be drawn out with 80 the drill. The front face 37 of each bit is in alinement with the front face 38 of each coal-conveyer thread, so that the coal cut loose by the bits will slide readily along said front faces 38 and be carried outwardly by the coal-conveyer threads as the drill is rotated.

By arranging a set of graduated bits in rotation I provide means whereby the bits will 85 cut freely and not choke, as would be the case if the bits were all alike or if only a single bit 90 was used. By using two key-seats 12 and 13 upon the feed-screw 11 I balance the friction between the feed-screw and the feed-nut, thereby avoiding the tendency to stick and the tendency to bend the feed-screw. 95

The drill-shank 14 with the conveyer-threads may be cast or formed in any suitable way, and by attaching the bits directly to the drill-shank without the interposition of the chuck I greatly simplify and cheapen the construction. 100

One of the great advantages of my coal-drill is the fact that the core 35 may be broken loose from the coal bank and removed in chunks instead of being cut up and pulverized, thus greatly reducing the amount of cutting to be done by the bits. 105

It is important that the threads upon the

feed-screw in the nut that operates the feed-screw be squared in cross-section, as shown. This makes a much stronger thread and adds to the life of the machine.

5 I claim—

1. In a coal-drill: the drill-shank 14 having the straight bore 15; the head 16 upon the drill-shank, and having an opening 17; the coal-conveyer threads 20 21 22 extending from 10 point of the drill-shanks to the head; the bit-holders 23 24 25 at the back sides of the threads and having sockets to receive the shanks of the bits; bits mounted with their shanks in said sockets; and set-screws screw-seated in 15 bit-holders to hold the bits in place.
2. In a coal-drill: a hollow drill-shank 14;

the coal-conveyer threads 20 21 22 upon drill-shank; of bit-holders 23 24 25 at the back sides of the coal-conveyer threads, and having sockets to receive the shanks of the bits; bits 28 29 30 mounted in the bit-holders, said bits being graduated in length and width; the widest bit being the shortest, and the narrowest bit being the longest.

In testimony whereof I have signed my name 25 to this specification in presence of two subscribing witnesses.

CHARLES W. COWELL.
